COMBINATION SAFETY RAZOR AND HAIR TRIMMING DEVICE

Leo A. Kearney, Palisades Park, N. J.

Application August 20, 1951, Serial No. 242,640

1 Claim. (Cl. 30—31)

1

This invention relates to new and useful improvements in a combination safety razor and hair trimming device.

More specifically, the present invention proposes the construction of an improved combination safety razor and hair trimming device having the general appearance of a safety razor of the hoe-type and which employs conventional double edged razor blades in a manner so that the device can be used on one side for conventional shaving and on the other side for hair trimming purposes.

Still further, the present invention proposes constructing the device to include a cap for retaining a double edged razor blade in position on a guard which cap has on one side of its depended threaded shank a wide portion for pressing one cutting edge of the razor blade into shaving position with relation to the guard in a manner to permit that one cutting edge to be used for conventional shaving purposes.

Another object of the present invention proposes forming the cap on the other side of its depended threaded shank with a narrow portion for holding the other cutting edge of the razor blade in a position slightly spaced from the guard in a manner so that the other cutting edge can be used for hair trimming purposes.

The present invention further proposes the provision of a plate for insertion between the cap and the razor blade in a manner to hold both of the cutting edges of the razor blade in a normal shaving position with relation to the guard in a manner so that both edges can be used for shaving if desired.

It is a further object of the present invention to construct a combination safety razor and hair trimming device which is simple and durable, which is effective for its intended purposes and which can be manufactured and sold at a reasonable cost.

For further comprehension of the invention, and of the objects and advantages thereof, reference will be had to the following description and accompanying drawings, and to the appended claim in which the various novel features of the invention are more particularly set forth.

On the accompanying drawings forming a material part of this disclosure:

Fig. 1 is a perspective view of the combination safety razor and hair trimming device constructed in accordance with the present invention.

Fig. 2 is a plan view of Fig. 1.

Fig. 3 is an enlarged transverse vertical sectional view taken substantially on the line 3—3 of Fig. 2.

2

Fig. 4 is a view similar to Fig. 2, but showing the device with the auxiliary plate in position between the blade and the cap.

Fig. 5 is an elevational view of the device looking in the direction of the line 5—5 of Fig. 4.

Fig. 6 is a perspective view of the auxiliary plate, per se.

The combination safety razor and hair trimming device, according to the present invention, includes a guard 10 constructed to have the usual teeth 11 along its longitudinal side edges. The center of the guard is formed with an aperture 12 and the top face thereof has grooves 14 extending longitudinally in opposite directions from the aperture 12.

Rested on the top face of the guard 10, there is a conventional double edged safety razor blade 15 having an aperture 16 aligned with the aperture 12 of the guard 10. On opposite sides of the aperture 16, the blade 15 has slots 17 in alignment with the grooves 14 of the guard.

Positioned over the razor blade 15, there is a cap 18 which has depended from its bottom face a threaded shank 19. As is generally known, the shank 19 depends through the apertures 12 and 16 of the guard 10 and blade 15, respectively, and is threaded into the top of a knurled handle 20 for joining the parts together. The bottom face of the cap 18 on opposite sides of the shank 19 has aligned longitudinally extended ribs 21. The ribs 21 project through the slots 17 of the razor blade 15 and into the grooves 14 of the guard 10 for holding the parts from turning relative to one another about the threaded shank 19 as a pivot.

The shank 19 and the ribs 21 are located so that the cap 18 has one wide portion 18^a and one narrow portion 18^b located on opposite sides of the center line passing through the ribs 21. The wide portion 18^a of the cap 18 terminates just slightly inward of its respective cutting edge of the razor blade 15, see Figs. 2 and 3, for pressing and holding that cutting edge of the blade in proper shaving position with relation to the teeth 11 of the guard 10.

The narrow portion 18^b of the cap 18 terminates some distance inward of its respective cutting edge of the razor blade 15, as shown in Figs. 2 and 3. The narrow portion 18^b permits its respective cutting edge of the blade to assume a position raised slightly off the respective teeth 11 of the guard 10, as best shown in Fig. 3, so that the cutting edge can be used for hair trimming purposes.

The corners of the wide portion 18^a of the cap 18 are formed with the usual short depending lugs 25 which engage the adjacent corner notches 26

of the double edged razor blade 15 so as to assist in maintaining the blade rigidly in position between the guard 10 and the cap 18 when the razor is assembled.

Thus, it is apparent that the present invention provides in a single device an arrangement for holding a conventional double edge razor blade so that one of its edges can be used for shaving while the other is used for hair trimming purposes and which requires nothing more than rotation of the device on the axis of the handle 20 for bringing the edges into operative position.

In Figs. 4 to 6, there is illustrated an auxiliary plate 22 which can, if desired, be inserted into position between the razor blade 15 and the cap 18 for holding both of the cutting edges of the blade in shaving position with relation to the teeth 11 of the guard 10. The plate 22 is provided on its longitudinal center with an aperture 23 for passing the threaded shank 19 of the cap 18. Extending in opposite directions from the aperture 23, the plate 22 has slots 24 for passing the ribs 21 of the cap 18.

When the auxiliary plate 22 is in position between the razor blade 15 and the cap 18 its one longitudinal edge will be flush with the longitudinal edge of the wide portion 18^a of the cap 18 so as to hold the respective cutting edge of the blade in rigid shaving position with relation to the teeth 11 of the guard. The other longitudinal edge of the auxiliary plate 22 extends beyond the longitudinal edge of the narrow portion 18^b of the cap into close proximity to the other cutting edge of the razor blade. Thus, the other longitudinal edge of the plate 22 functions to press the other cutting edge of the razor blade 15 into shaving position with relation to the respective teeth 11 of the guard 10. However, the auxiliary plate 22 being somewhat flexible it does not hold the other cutting edge of the blade 15 as rigidly in shaving position as does the plate 22 and wide portion 18^a of the cap hold the said one cutting edge of the razor blade in shaving position. Therefore, with the auxiliary plate 22 in position one edge of the blade 15 can be used for closer shaving than the other edge.

From the foregoing description, it is apparent that the present device can be quickly interchanged so that the edges of the double edged razor blade 15 are held for alternate use for shaving and hair trimming or in which both edges are held in position for shaving only, by

the simple act of inserting or removing the auxiliary plate 22.

While I have illustrated and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new and desire to secure by United States Letters Patent is:

A device of the class described, comprising a guard having teeth along its opposed longitudinal sides and a center aperture, a double edged razor blade rested on said guard and having cutting edges extended parallel to said teeth, said blade having a center aperture aligned with the center aperture of said guard, and a cap positioned on said blade and having a threaded shank depended through said apertures to have a handle threaded thereon, said cap having a wide portion on one side of the shank and a narrow portion on the other side of said shank, said wide portion having its longitudinal edge located closely adjacent the respective cutting edge of the razor blade pressing that cutting edge in shaving position with relation to the respective teeth of the guard, said narrow portion having its longitudinal edge located inward of the respective cutting edge of the razor blade leaving that cutting edge free to assume a hair trimming position with relation to the respective teeth of the guard, and a detachable auxiliary plate for insertion between the razor blade and cap for holding both of the cutting edges of said blade in shaving position with relation to the teeth of said guard, said auxiliary plate having its one longitudinal edge flush with the longitudinal edge of the wide portion of said cap and its other longitudinal edge extended beyond the longitudinal edge of the narrow portion of said cap and into close proximity with the respective cutting edge of said blade.

LEO A. KEARNEY.
